UNITED STATES PATENT OFFICE.

ALLEN C. BENNERS, OF BIRMINGHAM, ALABAMA.

KNOCKDOWN CARRIER FOR FRAGILE RECEPTACLES.

1,091,907.

Specification of Letters Patent. Patented Mar. 31, 1914.

Application filed October 19, 1912. Serial No. 726,730.

To all whom it may concern:

Be it known that I, ALLEN C. BENNERS, a citizen of the United States of America, residing at Birmingham, in the county of Jefferson and State of Alabama, have invented certain new and useful Improvements in Knockdown Carriers for Fragile Receptacles, of which the following is a specification.

- 10 My invention relates to a novel improvement in means for making it possible to handle and transport fragile receptacles such as paper buckets or wood veneer receptacles, and my object is to produce a 15 knock-down carrier, the several parts of which can be very cheaply manufactured, can be freighted at a nominal expense in view of the small space required for shipment, and can be readily assembled to provide 20 a convenient and safe frame or carrier in which the fragile receptacle is received and by means of which it may be transported with as much convenience as in the case of the rigid metallic and wooden receptacles. 25 I have found that there are many uses in the arts for the inexpensive, and fragile receptacles, but the chief commercial difficulty in connection with these is to provide a sufficiently inexpensive means for handling them when filled. To this end I have devised a knock-down frame which is 30 formed principally or wholly of bent wire and which comprises a series of hoops or bands adapted to be detachably connected 35 to a wire or bent metal angular frame which tapers outwardly for nesting purposes and is notched or slotted to receive the rings and the loops for the supporting bail.

- My invention comprises the details of construction and arrangement of parts, which, in their preferred embodiments, are illustrated in the accompanying drawings forming a part of this specification, and in which:—
- 40 Figure 1 is a perspective view of one form of my bucket carrier in operating position with the receptacle indicated therein in dotted lines. Fig. 2 is a modified design in which the carrier is formed of bent wire.
- 45 Similar reference numerals refer to similar parts throughout the drawings.

According to my invention, as illustrated in Fig. 1, I bend a strip of metal to form the upright frame comprising diverging legs 1 which are connected at their bottom by a

crimped base portion 2. The legs 1 may be made to come above the top of the receptacle as shown, or they may be bent over the top to hold the receptacle in the carrier more securely. I provide at the bottom of 60 each leg 1, by bending the strip, a ring receiving seat or recess 3. A bottom or base ring 4 formed of bent wire is adapted to be forced through the opening left to give access to the recesses 3 and to be thereby detachably connected to the frame. This base ring is provided at opposite points with downwardly bent portions 5 which form legs so that the ring is supported on a level with the top of the crimped base 2. The 70 ring is preferably formed of wire of sufficient strength to assist the frame in supporting a receptacle 6 which is indicated by dotted lines. At one or more intermediate points the uprights 1 are provided with 75 ring receiving seats 7 which, like 3, have an opening just sufficient to receive each an intermediate circular ring 8, which is slightly larger than the ring 4, due to the divergence of the uprights 1. There may be as 80 many of these rings 8 as the particular use contemplated may require. Additional rings 4 in the bottom of the carrier may be used if desired which are secured in the same style notch as 7 and bent into the 85 crimped part 2 which affords additional strength to the bottom of the carrier. The upper ends of the uprights are provided with slots 9 and a top ring 10 is provided, which at opposite points is provided with 90 loops 11 which lie in the plane of the ring and are adapted to project through the slots 9 sufficiently to be engaged by the bail 12 which is provided with a handle 13.

In the form illustrated in Fig. 2 the design of the rings is the same as shown in Fig. 1, but instead of forming the upright frame of a strip of metal, I form it of wire which is bent in parallel strands forming upright legs 14 which are bent at 15 to provide the receiving recesses for the intermediate ring or rings 8. The wire is also bent to provide the receiving recesses 16 for the bottom ring 4 and is crimped at 17 to correspond with the portions 5 of the base ring to 100 form the bottom support for the carrier and to strengthen it. At the top the strands 14 converge and join overhead and the loops 11 of the ring 10 engage the top of the side loops and are engaged by the bail 12 in the 110

same manner as shown in Fig. 1. Projections 18 are provided for holding the loop 10 in its proper position.

The device is adapted to be knocked-down and the diverging disposition of the uprights 1 or 14 is designed to permit these parts to nest. It is also desirable that the upright frame should taper because the light and fragile carrier or receptacles will probably be designed also for nesting in shipment, the object being to produce at a minimum expense both for construction and shipment, means for transporting fluids or other materials in the light paper or fragile receptacle which may be destroyed after use if desired for sanitary purposes. The rings will occupy but small shipping space.

When it is desired to assemble the carrier for use the rings 4, 8 and 10 can be rapidly inserted in their respective receiving notches or seats and the bail 12 attached. The receptacle may then be set down into the carrier with its bottom resting upon the bottom ring or rings 4 and the cross pieces 2 or 17, and on lifting the bail the weight of the receptacle will hold all parts in assembled position and relationship and the whole may be conveniently transported. After use the rings may be readily detached from the upright frame. I prefer to make the openings for the notches 3, 7, 15 and 16 just sufficient for the rings to be forced through them without becoming thereby permanently connected.

Having thus described my invention, what I claim as new and desire to secure by Letters Patent, is:—

1. In a skeleton knock-down carrier, in combination, a base having narrow integral oppositely disposed arms which when upright form spaced side members, a ring forming the top encircling member of the carrier, and means to detachably connect said ring at opposite points to said side members, which means comprise a bail for the carrier, substantially as described.

2. In a skeleton knock-down carrier, in combination, a base having narrow integral oppositely disposed arms adapted to be bent upwardly to form spaced side members, a ring forming the top encircling member of the carrier, said side members being adapted to engage said top ring at opposite points and hold it horizontal, and a bail which engages said top ring and holds it against detachment from said side members, substantially as described.

3. In a knock-down carrier, a U-shaped integral bent metal frame comprising a horizontal central base portion and spaced upright side members slotted at their upper ends, a ring which forms the top encircling member of the carrier, and a bail, said ring and bail being inter-connected through said slots in the side members and serving there-

by to detachably connect the several members of the carrier.

4. In a knock-down carrier, a bent metal frame comprising a central base portion and upright arms which are spaced and oppositely disposed and each provided with an oblong transversely disposed slot at its upper end, a ring which by itself forms the top encircling member of the carrier and is disposed inside said arms, said top ring having loops bent outwardly at opposite points and adapted to be inserted through said slots and to engage the top wall thereof at spaced points to support the ring horizontally, and a bail having its lower ends disposed outside said arms and detachably connected to the outer ends of said loops, substantially as described.

5. In a knock-down carrier, an upright bent frame having side members which diverge outwardly for nesting purposes and which are provided with ring receiving seats at different elevations, rings adapted to be detachably engaged in said seats, and a bail from which the carrier is suspended.

6. In a knock-down carrier, a bent metal frame having a base and two uprights, seats on said uprights at different elevations, rings adapted to be detachably engaged and held in said seats, and a bail which is detachably connected to the top ring and locks it in engagement with said frame.

7. In a knock-down carrier, a bent metal frame comprising a base bent to form legs, and side members bent to form ring receiving seats at different levels, a heavy bottom ring adapted to be detachably engaged in the lowest seats and having portions thereof bent to form legs, an intermediate ring which is detachably engaged in an intermediate seat in each of said uprights, a top ring having outwardly bent loops, there being openings in the top of the uprights through which said loops are adapted to be passed, and a bail which engages the loops after they have been passed through the uprights.

8. In a knock-down carrier, a bent metal frame comprising a fluted base and outwardly flaring sides, a series of rings, and means to detachably connect said rings to said frame.

9. In a knock-down carrier, a bent metal frame comprising a fluted base and outwardly flaring sides, a series of rings, and means to detachably connect said rings to said frame, the bottom ring being bent at opposite points to form legs which, with the said base of the frame, serve to support the carrier.

10. In a knock-down carrier, a bent metal frame having its upright sides notched at different elevations to form inwardly opening ring receiving seats, rings formed of bent wire which are each adapted to engage in and be detachably supported in a series of

said seats in the uprights, and handle means for transporting the carrier, substantially as described.

11. In a knock-down carrier, a bent metal frame having its sides bent outwardly to form notches having openings disposed toward the center of the carrier, rings formed of bent wire which have a cross sectional diameter slightly less than the width 5 of opening giving access to its respective seat, there being top, intermediate and bottom rings, and the top and bottom rings, be-

ing of heavier and stiffer metal than the intermediate ring or rings, said rings being adapted to be seated in their respective sets 15 of notches, and means to hold the frame and rings in assembled position, substantially as described.

In testimony whereof I affix my signature in presence of two witnesses.
